John L. Ward,
ATTORNEY.

UNITED STATES PATENT OFFICE

ALBERT RIGBY, OF PATERSON, NEW JERSEY, ASSIGNOR TO GILT EDGE SILK MILLS OF NEW JERSEY, INC., OF PATERSON, NEW JERSEY, A CORPORATION OF NEW JERSEY

STOP MOTION FOR LOOMS

Application filed October 29, 1929. Serial No. 403,158.

This invention relates to looms having electrically actuated means to effect some operation, as one resulting in the stopping of the loom, when the weft or filling in the shuttle is exhausted. The principal object is to provide a core for the wound filling package which will be adapted to close the circuit with certainty when the filling has been depleted to a certain extent but not so far that on the last pick before the mentioned operation occurs the end of the filling will be left in the shed, unconnected with the shuttle.

In the drawing,

15 Fig. 1 is a plan of a shuttle equipped with a quill or core embodying my invention and showing certain parts of a loom also in plan and more or less diagrammatically;

Fig. 2 shows said quill or core;

20 Fig. 3 is an enlarged fragmentary view of said quill or core, partly in section, with one of the terminals or feelers of the circuit of the electrically actuated means; and

Fig. 4 shows a modified form of the quill 25 or core.

1 is the breast-beam of a loom, 2 the batten reciprocatory toward and from the breast-beam, 3 the shuttle, 4 the picker for the shuttle, 5 a bracket on the breast-beam in which 30 is supported, in the usual manner so as to yield from the batten each time the same moves toward the breast-beam, a pair of terminals or feelers 6, 7 springs normally urging said terminals or feeders toward the 35 batten, holding them in the position shown, 8 an electric circuit having said springs and a source of energy 9, and 10 any means to be actuated on closing said circuit, as to stop the loom or cause in some way filling replenishment. The feelers are caused to yield as mentioned by the pressure thereon of the quill 11 in the shuttle, which latter and the 40 near wall of the shuttle box 2a have as usual openings 12 and 13 to give the feelers access to the quill.

The butt portion of the quill or core—which portion receives the contact of the feelers—has a metal ferrule to form the medium 45 for electrically bridging the feelers and hence

closing said circuit when the filling A is exhausted.

This ferrule (referring, first, to Figs. 1 to 3) is formed by a length of wire 14 wound spirally from a point near the flange 11a of the core around the tapering butt 11b thereof to a point in the shank of the core more or less removed from the smaller end of said butt. To preserve the wire ferrule in fast relation to the quill, which as usual may be and preferably is of some yielding material as wood, preferably all of the following expedients are resorted to: A few of its convolutions at each end are by solder cemented circumferentially together as at 65 15, so that in each instance the convolutions affected form in effect an integral band; all the convolutions or whorls are further integrally united by a narrow strip of solder 16, which preferably extends spirally; the convolutions, being round in cross-section, form interior ribs, and these rest in grooves 17, which grooves may result from winding the wire tightly around the core so as to impress itself therein; and finally the end of 70 the wire at the smaller end of the ferrule is bent inward and set in a hole 18 in the core. All the solder bands are filed off smooth.

It is desirable in mechanisms of this class to have the end of the filling which is the end 80 first placed on the quill remain attached thereto when, on the feelers 6 contacting with the circuit-closing medium (here the ferrule) and the means 10 is consequently actuated, the last pick of the shuttle is effected, 85 so that the last shot of filling will be a complete shot and the end of the filling will not be left within the shed. It is possible by my invention to keep a reserve including said end attached to the quill until this last pick is 90 completed because the exterior surface of the ferrule is grooved, whereby the windings forming such reserve sink in the grooves and thus leave the ribs of the metal ferrule existing between its grooves exposed to the contact therewith of the feelers. It is not new to groove a metal circuit closing medium of a shuttle quill or core so that filling windings may be sheathed in this way, but it is 95 new to form the grooves as components of a 100

single spiral recess (as that existing exteriorly of my spirally wound ferrule), and to form this recess so that it shall progress spirally in the same direction as the windings are wound, as I in fact preferably do, whereby reaching-over of the filling from one to the next groove and the consequence that this condition might prevent closing of the circuit until not enough reserve was left to reach across the shed on the last pick are avoided. It is with this last consideration in mind that I form the solder band 16 spirally instead of truly axially of the ferrule; this band, by filling the grooves, prevents where it exists the sheathing of the windings, and if it extended axially it might find itself positioned opposite the feelers (at least in the case where, as usual, they occupy a horizontal plane) and so the filling might prevent their contact with the ferrule until the effective reserve of filling was too far exhausted. By arranging the band 16 spirally, or at any rate so that it will be oblique to the feelers according to the plane they occupy, I avoid its being a possible factor in the closing of the circuit occurring too late since thereby the feelers may straddle it or one at least fail to contact therewith.

In Fig. 4 the ferrule 19 is of sheet metal having a primary shape generally conforming to that of the butt-portion of the quill or core. Having slipped it over said butt-portion its edge 19a is peened over against the outer face of the flange 11a of the butt. This sleeve has the circumferential grooves 19b (here each formed in a plane) and if these are formed, as shown, by crimping the metal the consequent interior ribs resulting will interlock with grooves 20 in the core; these grooves may be pre-formed or result from the operation of crimping the ferrule after installing it on the core. The whorls existing between the grooves 19b receive the contact of the feelers.

Having thus fully described my invention, what I claim is:

1. In combination, a shuttle quill and a coil of circuit-closing material wound around the quill in a windings-receiving portion thereof.
2. In combination, a shuttle quill and a ferrule consisting of a coil of circuit-closing material wound around the quill in a windings-receiving portion thereof, said ferrule having windings-receiving grooves.
3. In combination, a shuttle quill and a coil of circuit closing material wound around the quill in a windings-receiving portion thereof, the convolutions of said coil having exterior windings-receiving grooves between them.
4. In combination, a shuttle quill and a ferrule on the windings-receiving portion thereof consisting of a series of circuit-closing whorls arranged close together having exterior narrow grooves between them.

5. A wound shuttle package comprising a quill having an exterior spirally grooved circuit closing surface in its windings-receiving portion and windings of filling wound around the quill in engagement with said surface and spirally in the same rotative direction as the grooving of such surface. 70

6. In combination, a shuttle quill, a series of whorls of circuit-closing material fitted on the quill in a windings-receiving portion thereof, end whorls is in the series being cemented together. 75

7. In combination, a shuttle quill, a series of whorls of circuit-closing material fitted on the quill in a windings-receiving portion thereof, and a strip of cementing material joining whorls of the series together. 80

8. In combination, a shuttle quill, a series of whorls of circuit-closing material fitted on the quill in a windings-receiving portion thereof, and a strip of cementing material joining whorls of the series together and extending spirally of the series. 85

9. In combination, with a pair of feelers of an electric weft-stop motion of a loom, a shuttle, a quill in the shuttle, a series of whorls of circuit closing material fitted on the quill in the windings-receiving portion thereof and adapted to be contacted by the feelers, and a strip of cementing material joining the whorls of the series together and arranged obliquely to a plane common to the feelers. 90

10. A bobbin having a body and having a length of electric conducting material wound helically thereon to present a continuous conducting surface when uncovered by weft absence. 100

In testimony whereof I affix my signature.

ALBERT RIGBY.
